ELECTRIC SAUNA BATH HEATER

Gordon M. Dow, North, and Lowell T. Swenson, Thief River Falls, Minn., assignors to Dow-Key Company, Inc., Thief River Falls, Minn., a corporation of Minnesota

Filed Jan. 16, 1964, Ser. No. 338,086
12 Claims. (Cl. 219—378)

This invention relates generally to baths and is more particularly directed to apparatus for providing a sauna-type bath which originated in Finland.

An object of the present invention is to provide an improved apparatus which forms a part of a complete installation which may be installed, for example, within the average home and which may be constructed so that it may be acquired and installed within the range of prices attractive to the average homeowner who is interested in obtaining the benefits of a sauna bath located in his own home.

Another object of this invention is to provide equipment for utilization in a sauna bath which is relatively inexpensive to purchase and operate.

A further object of this invention is to provide improved apparatus for use in individual enclosures, or cubicles, for providing sauna-type baths.

A still further object of this invention is to provide an improved heater apparatus for use in a sauna-type bath.

A further object of this invention is to provide a safe heater apparatus for a sauna-type bath.

It is a still further object of this invention to provide a heater for use in a sauna-type bath enclosure which provides a more accurate control over the atmosphere which must be created to enjoy the benefits of a sauna-type bath.

These and other objects of our invention will become apparent from a consideration of the appended specification, claims and drawings, in which:

FIG. 1 is a side elevational view, partly broken away, of a heater which may be utilized in a sauna-type bath installation.

FIG. 2 is a top plan view of the heater shown in FIG. 1.

FIG. 3 is a side sectional view taken along section line 3—3 in FIG. 1.

FIG. 4 is an electrical schematic drawing illustrating one embodiment of control circuitry which may be utilized in connection with the apparatus shown in FIGS. 1, 2 and 3.

FIG. 5 is a perspective sketch of a complete sauna-type bath apparatus.

Referring now to the drawings, and particularly to FIG. 5, there is shown a complete sauna bath installation in which an enclosure, indicated generally by the reference numeral 50, is provided with an access door 52 and a platform, shown as a series of steps, 51 upon which the user of the sauna bath installation may be seated during the time the bath is in progress. A heater, indicated generally by the reference numeral 10, and having a control box assembly 40 adapted for connection to a suitable source of electrical energy through conductors 14, is in position below a source of liquid 12, having a valve 13 which is adapted to regulate the flow of liquid down onto the top of the heater apparatus 10. In many uses of our apparatus the fluid used to create the desired atmosphere may easily be applied manually to the top of heater 10 from a suitable source or container (not shown). Control box 40 is also connected to a wall-mounted temperature responsive means 11 for purposes to be explained below.

As will become apparent from a consideration of the operation of the apparatus shown in FIGS. 1, 2, 3 and 4, explained in detail below, the general operation of the

complete sauna bath shown in FIG. 5 is as follows: the subject, or user, enters enclosure 50 and energizes the heater apparatus 10, through suitable means (not shown) and the temperature in the enclosure rises to a point determined by the setting of the temperature responsive apparatus 11 and heated air, during this time, is circulated through heater apparatus 10 by the use of a blower 15, which takes air from the lower portion of the room and passes it through heater apparatus 10 and vents it back into the room through the plurality of slots 21 shown at the sides of heating apparatus 10. From time to time, and as desired by the subject, suitable amounts of a liquid, for example water, are added to the top of heating apparatus 10 and the liquid is immediately vaporized and re-expelled and added to the atmosphere in enclosure 50. The temperature of the air therein is held at a predetermined level and, as will be explained below, the vapor is generated at a substantially constant predetermined temperature so that the subject may effect a balance and maintain the desired atmosphere, as determined by any particular subject, within the enclosure for as long as is desired.

Referring now to FIGS. 1, 2, and 3 of the drawing, heating apparatus 10 is comprised of an outer housing 20 which is open at its top and is provided with a plurality of louvered slots 21 near the upper outside periphery to allow for the escape of heated air as will be explained below. Outer housing 20 is also provided with a plurality of legs 22 which are provided and adapted to support heating apparatus 10. A second, or inner housing 30 is suitably mounted within outer housing 20. Inner housing 30 may be comprised of suitable material which exhibits low thermal conductivity. Inner housing 30 is formed with an upwardly extending opening at its top and with at least one inlet opening 55 and at least one outlet opening 54 at the bottom end. First and second chambers are defined on the interior of inner housing 30 by the suitable positioning and fastening of a heating means indicated generally by the reference numeral 25. Heating means 25 is comprised of a substantially flat central portion which extends in proximity to and engages the sides of inner enclosure member 30 so as to define the upper and lower chambers noted above. A plurality of generally conical protuberances 26 extend upwardly from the top surface of the central portion of heater means 25 and lie within the upper chamber and enclosure 30. A like plurality of generally conically shaped protuberances depend downwardly from the lower surface of the center portion of heater member 25 to fill the lower chamber and inner enclosure member 30. A resistance heating element is shown positioned in an appropriate channel 27 formed in the center of the center portion of heater member 25. This resistance heating element may be formed integrally with heater member 25 by a suitable process, for example casting. It has further been noted that a suitable material for heater member 25 is a high temperature alloy of aluminum which is selected to withstand the normal operating temperatures of the heater unit. It may further be noted that inner housing 30 may be comprised of a plurality of layers of material 31 and 32 to provide a housing which has a low thermal conductivity coefficient. For example, layer 31 may be comprised of a suitable dielectric material which has low heat transfer characteristics such as powdered alumina, asbestos or the like. A condition responsive means 16 may be utilized to sense the temperature on the top surface of the center portion of heating member 25 and is shown, by way of example, as a snap-acting thermostat which may be utilized to directly control the flow of current to heating element 17 as shown in FIG. 4. A perforated cover member 24 having a plurality of perforations 41 is shown in position on

the top of the top chamber in inner housing member 30 and the spaces between the upwardly depending protrusions 26 within the upper chamber may be filled with a suitable material having high heat transfer characteristics, for example, marble chips or aluminum balls or shavings. It should be noted that inner housing 30 is divided into two chambers by suitable mounting means (not shown) for heater member 25 which will provide a fluid type seal between the upper and lower chambers. A control box 40 is attached to outer housing 20 and contains suitable devices and apparatus for providing the interconnections between the conductors of the various components comprising our invention. Upon becoming familiar with the principles of our invention, and with a consideration of the schematic diagram of FIG. 4, the illustrated apparatus and may others will become apparent to those skilled in the art for controlling the operation of our apparatus. In FIG. 4 there is shown a condition responsive means 11, also indicated by the reference numeral T₁, connected to control box 40 through a pair of conductors; a pair of terminals 14 adapted for connection to a suitable source of electrical energy; a pair of conductors 66 connected to blower means 15; a pair of conductors connected to resistance heating element 17; and a pair of conductors connected to condition responsive means 16, also indicated by the reference numeral T₂.

A blower 15 includes an inlet 56 and an outlet 57 which is shown attached to inlet 55 on inner housing member 30 and the flow of air is driven by blower 15 as indicated generally by the arrows, through blower 15, into the lower chamber on inner housing 30, around the staggered downwardly depending protrusions 28 on heater member 25, out of outlet opening 54 and around the bottom and up the sides of the inside of housing member 20 and thence through louvered openings 21 into the interior of the enclosure in which the heating apparatus is utilized. It may be desirable under some circumstances, to maintain a predetermined relationship between the area of inlet openings 55 and outlet openings 54 to provide for efficient transfer of heat energy to the air as it passes through the lower chamber on inner housing 30. A smaller area on the outlet openings provides for a form of time delay which serves to increase the temperature of the air leaving the outlet opening.

While we have shown and described our heater in a particular embodiment, it is anticipated that other forms of apparatus, such as will be set forth below by way of illustrative examples, will occur to those skilled in the art and it is contemplated that these and other modifications properly fall within the scope of our invention.

In one operative embodiment of our invention, apparatus similar to the inner housing 30 was utilized. Suitable legs or support means were attached directly to a housing having a single insulated wall. The upper and lower chambers as illustrated in the drawing were present and the general overall operating characteristics were substantially the same as noted above in connection with the illustrated embodiment.

A further modification may be obtained by removing the horizontally oriented lower portion of inner housing 30 and attaching the outlet of the blower directly to the bottom of housing 20. In apparatus constructed according to this modification, the relationship between the inlet and outlet openings, as noted above, should be retained. The dimensions of lower protrusions 28 may also be modified to place the lower ends thereof in closer proximity to the bottom of housing 20.

In FIG. 4 the schematic drawing shows a pair of terminals 14 connected across a suitable source of alternating current and electrical resistance heating element 17 connected in series with condition responsive means 16 and the energization of resistance 17 is controlled thereby. In a like manner blower 15 and condition responsive means 11 are connected in series across terminals

14 and the operation of blower 15 is controlled in accordance with the operation of the condition responsive means. Both of the condition responsive means 11 and 16 may be suitable thermostats which may be adjustable at the will of an operator.

In operation, it has been determined that a suitable temperature for the enclosure of the sauna bath is not less than 100° F. and up to 160° F. or more dependent on the user and this is controlled, upon energization of the heating apparatus, by condition responsive means 11 which serve to energize and deenergize blower 15 in a manner which will maintain the enclosure at the predetermined desired temperature. It has also been noted that one suitable operating temperature for heating means 25 is a relatively constant 600° F. Heating means 25 not only serves as a source of heat energy for the air which is passed through heating apparatus 10 by means of blower 15, but also provides a source of heat energy for vaporizing the liquids added through the top of the apparatus to the upper chamber of inner housing 30.

It is understood that suitable modifications may be made in the structure as disclosed, provided such modifications come within the spirit and scope of the appended claims. Having now therefore fully illustrated and described our invention, what we claim to be new and desire to protect by Letters Patent is:

1. A heater for sauna bath enclosures comprising in combination: a horizontally disposed, substantially planar heating element having a plurality of upwardly and downwardly extending protrusions formed integrally therewith; heating means disposed interiorly of said heating element; a housing therefor, said housing being adapted to surround and enclose said heating element whereby said housing is divided into upper and lower chambers, each containing corresponding upwardly and downwardly extending pluralities of said protrusions, the lower chamber having inlet and outlet openings for the transmission of air therethrough and the upper chamber having an upwardly directed opening for receiving liquids to be vaporized and also containing a plurality of said protrusions on the heating element; and means for supplying air under pressure connected to said inlet opening.

2. The apparatus of claim 1 in which the upper chamber is filled with particles of material exhibiting good heat transfer characteristics.

3. The apparatus of claim 2 in which the upwardly directed opening in the upper chamber is covered with a perforated screen.

4. The apparatus of claim 1 in which said air supplying means comprises a blower mounted on said housing to direct air into the inlet opening.

5. The apparatus of claim 1 in which the area of the outlet opening is less than the area of the inlet opening.

6. The apparatus of claim 1 in which the housing is comprised of material exhibiting low heat transfer characteristics.

7. The apparatus of claim 1 in which the housing is mounted within a second housing and the second housing includes a plurality of openings adapted to receive air from the outlet opening on the housing for said heating element and to vent the same to the atmosphere.

8. The apparatus of claim 1 in which the heating means includes electrical means and a thermostat is mounted on the surface of said heating means for maintaining the same at a predetermined temperature.

9. A heater for a sauna type enclosure comprising in combination: a heater comprised of a horizontally disposed substantially planar base member having a plurality of upwardly and downwardly extending protrusions dependent therefrom, said heater including electrical means therein for heating the same and temperature responsive switching means on the upper surface thereof, said electrical heating means and temperature responsive switching means being connected in series intermediate a pair of terminals adapted for connection to a suitable source

of electrical energy; a housing adapted to surround and receive said heater whereby the downwardly depending protrusions are enclosed in a lower chamber and the upwardly extending protrusions are enclosed in an upper chamber, said lower chamber having inlet and outlet openings and said upper chamber having an upwardly directed opening; a blower, including current responsive motor means, connected to direct air under pressure into the inlet openings in said lower chamber; further temperature responsive means disposed outside of said enclosure and remotely therefrom; and circuit means interconnecting said motor means and said further temperature responsive means to said source of electrical energy.

10. The apparatus of claim 9 in which the protrusions on the heater are in opposed, staggered rows.

11. The apparatus of claim 10 in which the upper chamber is filled with particles of material exhibiting good heat transfer characteristics.

12. The apparatus of claim 9 in which the housing is surrounded by a further housing having an upwardly directed opening and an opening adapted to coat and register with the inlet opening in the lower chamber in said housing and including a plurality of openings in fluid

transmitting relationship with the outlet opening in the lower chamber of said housing.
